UNITED STATES PATENT OFFICE

VICTOR MAUCK, OF MERION, PENNSYLVANIA

GAS WATER HEATER

Application filed February 26, 1927. Serial No. 171,237.

My invention is particularly applicable to heaters of the class described in Letters Patent of the United States Nos. 1,542,573 and 1,587,177 granted to Arthur E. Paige of Philadelphia, Pennsylvania; operative to maintain a body of water heated to a predetermined temperature; by a burner supplied with gas under control of a thermostatically operative valve arranged to minutely regulate a small volume of gas passing to the burner and to temporarily permit the passage of a much larger volume of gas to the same burner. Such heaters have been largely manufactured and sold, under my direction, and I find from such experience that if the thermostatically controlled valve is adjusted to maintain the minimum supply of gas when the water reaches the predetermined temperature; a momentary abnormal demand upon the gas supply in the neighborhood of such a heater may diminish the gas pressure at the heater to such a degree that such minimum flames are extinguished, without any means for automatically shutting off the ensuing flow of unconsumed gas, which flow is, of course, augmented by the continued operation of the thermostatically controlled valve as the temperature of the water falls.

Therefore, it is the object and effect of my invention to provide means, in coordinated relation with such a thermostatically controlled valve, adapted to cut off the supply of gas to the latter if and when the flames at the burner are thus accidentally extinguished.

As hereinafter described, the object aforesaid is attained by providing a pilot flame supplied through a bypass around the thermostatically controlled valve which determines the supply of gas to the main burner, and associating with such pilot burner and its automatic controlling mechanism a diaphragm valve through which the supply of gas is delivered both to the main burner and to the pilot burner; said diaphragm valve being constructed and arranged to be operated by back pressure of the gas to shut off the supply of gas to the main burner, as a consequence of the automatic shutting off of the supply of gas to the pilot burner orifice.

My invention includes the various novel features of construction and arrangement hereinafter more definitely specified.

In said drawings; Fig. I is a plan view of a gas water heater of the thermostatically controlled type aforesaid, conveniently embodying my invention. Fig. II is a plan sectional view of said heater, taken on the line II, II in Fig. III. Fig. III is a vertical sectional view of said heater, taken on the line III, III in Figs. I and II. Fig. IV is a fragmentary vertical sectional view, taken on the line IV, IV in Fig. II, but on a larger scale, showing the construction and arrangement of the pilot burner and diaphragm valve, and their appurtenances. Fig. V is a vertical sectional view of the diaphragm valve, taken on the line V, V in Fig. I. Fig. VI is a sectional view, taken on the line VI, VI in Fig. V; showing the stop and vent valve. Figs. VII and VIII are sectional views showing a modified form of pilot burner.

In said figures; the water container comprises the cylindrical metal shell 1 having the cold water inlet 2 and the hot water outlet 3 at the top thereof, and the combustion chamber 5 at the bottom thereof. The diaphragm 6 forms the bottom closure of the water space 7 in said container 1, and the top of said combustion chamber. The flue 10 has its lower end connected with said diaphragm 6, and extends to the outer atmosphere, through said water container, parallel with, but eccentric to, the axis of said container shell 1.

The hollow oblate water spreader 11 is mounted in eccentric relation with said diaphragm 6, and extending below the latter in said combustion chamber; having at its upper portion, in coaxial relation, an externally screw threaded neck flange 12 surrounded by the internally and externally screw threaded fusible metal sleeve 13 extending in a corresponding opening surrounded by the flange 14 in said diaphragm 6. Said spreader has, in coaxial relation therewith, but eccentric to said container, the socket 15, engaged with the lower end of the hot water riser pipe 16, which latter terminates a short distance 100

above said diaphragm 6 and has perforations 18 through which the heated water, from said spreader, is delivered laterally into said space 7. Said spreader also has two diametrically spaced cold water inlet nozzles 20, at respectively opposite sides of said socket 15 and in communication with the water space 7 through said spreader neck 12.

The water drain pipe 21 extends from the bottom of said spreader 11 to the exterior of said combustion chamber 5, where it is provided with the drain cock 22 through which sediment may be withdrawn from said spreader. The collar 23 encircles said drain pipe 21 and is provided with the set screw 24 to secure it in adjusted position, as a support for the main gas burner 26. Said main gas burner is a hollow horseshoe-shaped body, having the radially extending cross bars 27 forming axial bearings 28 embracing said drain pipe 21 and resting upon said collar 23. The mixing tube 30 extends from said burner body 26 in eccentric tangential relation thereto, but in diametrical relation with said container 1 and combustion chamber 5, as best shown in Fig. II, and is slip fitted over the gas supply tube 31. The arrangement is such that said burner 26 may be readily withdrawn and replaced laterally with respect to said pipe 21 and collar 23 which support it.

As indicated in Fig. I, the gas conduit 33 leading to said burner 26 has the automatically, thermostatically operative, valve 34 arranged to control it in accordance with the expansion and contraction of the thermostatic element in the tube 35 which is rigidly connected with said valve. Said tube 35 extends diametrically in the water space 7 in said container shell 1 between said flue pipe 10 and hot water riser pipe 16, and said valve 34 and tube 35 are detachably connected with said container shell 1 by the screw thread 36 on the valve casing engaging the spud 37 in said shell.

I find it convenient to provide said gas supply conduit 33 with the manually operative stop cock 39 leading to said conduit 31 between said automatic valve 34 and said burner 26; and also to provide the manually operative needle valve 40 in said conduit 31 between said stop cock 39 and said burner 26 to control the effective area of the gas inlet port within said conduit 31.

The construction and arrangement above described are such that after the gas is lighted at the main burner 26, the gas supply is automatically varied, by the operation of the thermostatically controlled valve 34, in accordance with the temperature of the water in the reservoir space 7, to maintain the mass of water in said space at a predetermined temperature, say, 170° F.; the supply of gas being automatically increased when hot water is withdrawn from the outlet 3 with consequent inflow of cold water through the

inlet 2, and diminished as the water is raised to the predetermined temperature by the heat from said burner 26; the flames at the burner 26 being reduced to the minimum height when the temperature of the water is raised to the maximum. As aforesaid; when the flow of gas to the main burner 26 is thus reduced to the minimum by the operation of the valve 34; the flames 41 at the burner 26 are liable to be accidentally extinguished by momentary lessening of the pressure of the gas in said supply pipe 33 from any cause; for instance, by an abnormal demand upon the gas supply in the neighborhood of the heater, and although means are provided, as above described, whereby the flow of gas to the burner may be manually shut off; the structure described does not include any means for apprising the user that the flames 41 have been thus extinguished at the main burner 26 and that the gas is flowing therethrough unconsumed and with increasing volume.

Therefore, in order to maintain the main burner 26 practically continuously operative under such abnormal fluctuations in gas pressure; I provide means to relight it automatically, including the pilot burner 42 which is supplied with gas independently of said valve 34, so that the pilot flame 43 may remain lighted when the flames of the main burner 26 are extinguished; and provide, in coordinated relation with both the main burner 26 and said pilot burner 42, means for automatically shutting off the supply of gas to both, if and when the flames of both of said burners are accidentally extinguished.

Said pilot burner 42 is a metallic tube, preferably copper, which is detachably rigidly mounted in the base 45 which is conveniently provided with the clamp member 46 for cooperation with the clamp member 47 with which it is connected by the screws 48 to tightly embrace said water pipe 21 and thus maintain said base 45 in predetermined vertical position with respect to the burner 26. Said tube 42 encases the carbon rod 50 which is arranged to cooperate with said tube 42, as a thermostatic couple, to close the jet orifice 52, through which gas is normally supplied to said pilot flame 43; such closure being effected at a predetermined temperature which may be adjustably varied. I prefer to form said jet orifice 52 in the cap 53 on said tube and to provide the valve 54 with spring means 55 arranged to normally open said orifice by retraction of said valve 54 from the seat 56; the stem of said valve 54 being fluted to permit the passage of gas to said orifice from the tubular space 57 in said tube 42. Said valve 54 is thus spring pressed downwardly upon the upper end of said carbon rod 50; the coefficient of expansion of which, under increments of temperature, being such that it remains of substantially constant length throughout the range of tem-

perature to which it is subjected. On the contrary, the coefficient of expansion of the tube 42 is such as to vary its length to open and close said orifice at predetermined temperatures which may be adjustably varied by changing the relative position of said carbon rod 50 in said tube which rests upon the adjusting screw 58 which is tightly fitted in said base 45.

10 The space 57 within said pilot burner tube 42 is supplied with gas, through the conduit 59, preferably a flexible metal tube, rigidly connected at one end with said base 45 and which extends to the casing 60 of the plug valve 61. Said valve casing 60 is attached to the cover 62 of the diaphragm valve casing 63, and has the gas passage 64 leading from the chamber 65, in said cover 62, above the diaphragm 67, to the pilot burner 42, and has the gas vent 68 opening directly to the atmosphere. Said valve 61 has the port 69, and may be manually turned to vary the flow of gas from said chamber 65 to the pilot burner, or to open said vent 68 and thus relieve the diaphragm 67 of gas pressure above it, when the pilot burner is closed.

Said diaphragm valve casing 63 has the passageway 70 leading to said gas pipe 33, leading to the main burner 26, and gas for both burners is supplied through the pipe 71 in communication with the passageway 72, in said casing 63, terminating in the seat 73 for the diaphragm valve 75. Said valve 75 is adapted to close said passageway 72 and shut off the supply of gas to the main burner 26 whenever the pressure above said diaphragm 67 equals the pressure below it, which is when said pilot burner orifice 52 is closed. However, when either said orifice 52 or said vent 68 is open, said diaphragm is relieved of back pressure of the gas, and is lifted and upheld by the gas flowing through the passageway 72 to the main burner 26; thus permitting such supply of gas to said burner 26 to be variably controlled by the thermostatic valve 34 as above described.

Said valve 75 has the "bleed" port 76 continually permitting the passage of gas for the pilot flame 43 when the pilot orifice 52 is open. However, when said orifice 52 is closed by the operation of the thermostatic couple 42, 50, as above described, the gas pressure above the diaphragm 67, in the chamber 65, becomes equal to that below said diaphragm and the diaphragm valve 75 closes upon its seat 73.

Said gas controlling devices operate as follows: The adjusting screw 58 may be set so that the relative position of the carbon rod 50 in the copper tube 42 is such that the pilot orifice 52 is closed at 400° F., but opened at any higher temperature. The stop cock 39 and vent 68 of the valve casing 60, being opened, gas is supplied from the pipe 71 through the diaphragm valve casing 63, pipe

33, valve 34 etc., to the burner 26 and may be manually ignited at the latter. Combustion of gas at the main burner 26, immediately heats the pilot burner tube 42 above 400° F.; opens the orifice 52, and ignites the gas thereof to form the pilot flame 43. Thereafter, momentary diminution of the gas pressure, which may be sufficient to extinguish the flames 41 of the main gas burner 26, fails to extinguish the pilot flame 43 which is separately supplied as aforesaid. Consequently, when the normal gas pressure is restored, the gas escaping through the orifices 78 of the burner 26 is relighted in flames 41 by the pilot flame 43. Similarly, if said pilot flame 43 be accidentally extinguished, while the main burner flames 41 are present; the gas issuing from said pilot burner orifice 52 is relighted by said flames 41. However, if both the flames 41 and 43 be accidentally extinguished; the temperature of the thermostatic pilot burner tube 42 immediately falls to 400° F., with the effect of closing the pilot burner orifice 52; which causes the back pressure of gas to accumulate above the diaphragm 67 in the chamber 65 and thus permits the diaphragm valve 75 to close upon its seat 73 and thus shut off the supply of gas to the burner 26.

To relight the burners, the valve 61 may be turned ninety degrees counterclockwise from the position shown in Fig. VI, to open said vent 68, thus releasing the gas pressure above the diaphragm 67; whereupon, said diaphragm valve 75 is opened by the gas pressure from the supply pipe 71; and the gas issuing through the main burner 26 may be manually relighted in flames 41. The heat from the main burner 26 reopens the pilot burner and restores the pilot flame 43.

Although I prefer to provide the pilot burner with means for changing the relative position of the thermostatic elements 42 and 50, including the screw 58 above described; it is to be understood that said elements 42 and 50 may be made of predetermined standard length and such adjusting means be omitted. Moreover, although I find it convenient to provide the upper end of said pilot burner tube 42 with a primarily separate cap 53 in which the pilot burner orifice 52 is formed, and to control the latter by the spring pressed valve 54 actuated by coordination with said carbon rod 50; it is to be understood that said pilot burner orifice may be otherwise located and coordinated to be opened and closed by the difference in coefficients of expansion of said thermostatic elements 42 and 50. Furthermore, I may provide a hood 80 over the pilot flame 43 to deflect it over the burner 26 and directly convey the heat to the thermostatic tube 42.

Said pilot burner 42 requires a space of greater vertical extent than is available in some forms of gas water heaters. Therefore,

I have shown, in Figs. VII and VIII, a modified form of my invention, wherein the pilot burner tube 82 is substituted for the burner tube 42 aforesaid, but otherwise connected as said tube 42 is shown and described. Said tube 82 is provided with the cap 83 having the port 84 in the valve seat 85 which is controlled by the plunger valve 86 operatively connected with the thermostatic couple 87 and 88, which is a normally plane strip and supported at its ends upon the arms 89 of said cap. Said structure is arranged to close said port 84 at a predetermined minimum temperature, for instance, 400° F., and, when heated above that temperature, said couple 87 is expanded upwardly, as indicated in dotted lines in Fig. VIII, so as to uplift the valve 86 and permit the passage of gas through said port 84 to the orifice 90 where it is ignited to form the pilot flame 91 which performs the same function as the pilot flame 43.

Therefore, I do not desire to limit myself to the precise details of construction and arrangement herein set forth, as it is obvious that various modifications may be made therein without departing from the essential features of my invention, as defined in the appended claims.

I claim:

1. In a gas burner, the combination with a metal tube, having a gas jet orifice; of a valve for said orifice; a spring tending to open said valve; a carbon rod in said tube and arranged to close said orifice, by said valve, at a predetermined temperature of said tube; by reason of the difference in coefficients of expansion of said tube and rod.

2. In a gas burner, the combination with a metal tube, having a gas jet orifice, at one end thereof; of a valve for said orifice; a spring tending to open said valve; a carbon rod extending coaxially in said tube and arranged to close said orifice, by said valve, at a predetermined temperature of said tube; by reason of the difference in coefficients of expansion of said tube and rod.

3. In a gas burner, the combination with a metal tube, having a gas jet orifice; of a valve for said orifice; a spring tending to open said valve; a carbon rod in said tube and arranged to close said orifice, by said valve, at a predetermined temperature of said tube; by reason of the difference in coefficients of expansion of said tube and rod; and means arranged to adjustably vary the relative position of said tube and rod, and thereby vary the temperature at which said orifice is closed.

4. In a gas burner, the combination with a base; of a metal tube detachably rigidly mounted on said base; a cap on said tube having a gas jet orifice; valve means in said tube movable to close said orifice; spring means arranged to normally open said orifice; and

a carbon rod in said tube, in cooperative relation with said valve means; whereby said orifice is automatically closed when said tube is at a certain temperature.

5. In a gas burner, the combination with a base; of a metal tube detachably rigidly mounted on said base; a cap on said tube having a gas jet orifice; valve means in said tube movable to close said orifice; spring means arranged to normally open said orifice; a carbon rod in said tube, in cooperative relation with said valve means; and a set screw in said base, movable to adjust said rod toward and away from said orifice; whereby said orifice is automatically closed when said tube is at a certain temperature, which may be variably determined by the adjustment of said screw.

6. The combination with a pilot gas burner having a jet orifice, of a main gas burner, in cooperative relation therewith; means, common to both burners, arranged to supply gas thereto, including a valve casing having separate gas outlets, respectively leading to said burners, and a single gas supply inlet, common to both of said outlets; and means arranged to vary the flow of gas to said main burner, independently of said pilot burner, including a thermostatically controlled valve, between said main burner and the valve casing outlet leading to that burner; a flexible diaphragm in said valve casing, separating said outlets, and having said inlet upon one side thereof; and a valve carried by said diaphragm, adapted to automatically shut off the flow of gas, through said casing outlet, to said main burner, by movement of said diaphragm, when said orifice is closed.

7. The combination with a pilot gas burner having a jet orifice; of a main gas burner, in cooperative relation therewith; means, common to both burners, arranged to supply gas thereto, including a valve casing having separate gas outlets, respectively leading to said burners, and a single gas supply outlet, common to both of said outlets; and means arranged to vary the flow of gas to said main burner, independently of said pilot burner, including a thermostatically controlled valve, between said main burner and the valve casing outlet leading to that burner; a flexible diaphragm in said valve casing, separating said outlets, and having said inlet upon one side thereof; a valve carried by said diaphragm, adapted to automatically shut off the flow of gas, through said casing outlet, to said main burner, by movement of said diaphragm, when said orifice is closed; said diaphragm valve having a bleed port leading

from said common gas inlet to the casing outlet leading to said pilot burner; whereby, said pilot burner is continually in communication with said gas supply inlet, through said bleed port; but said main burner is only

in communication with said gas supply inlet when said pilot burner orifice is open.

8. The combination with a main gas burner and a pilot gas burner, in cooperative relation; of a thermostatic couple, arranged to control said pilot burner in accordance with the temperature of the latter; means arranged to supply gas to both burners, including a valve casing having gas outlets, leading to the respective burners, and a common gas inlet; a flexible diaphragm in said valve casing between said gas outlets, and having said gas inlet upon one side thereof; a valve carried by said diaphragm, arranged to control the passage of gas through the respective casing outlet to said main burner; and a constantly open bleed port leading from said gas inlet to the casing outlet leading to said pilot burner; whereby said diaphragm valve is normally held open, by the pressure of gas from said inlet, to permit the supply of gas to said main burner, when said pilot burner is open; but said diaphragm valve is closed, to shut off the gas to said main burner, when said pilot burner is closed.

9. The combination with a main gas burner; of a pilot burner; means controlling the relative volumes of the supply of gas to both burners, and including a valve casing inclosing a diaphragm having a gas supply inlet and an outlet to said main burner upon one side of said diaphragm, and an outlet to said pilot burner and a vent to the atmosphere, upon the other side of said diaphragm; and means movable to open and close said vent.

10. The combination with a main gas burner; of a pilot burner; means controlling the relative volumes of the supply of gas to both burners, and including a valve casing inclosing a diaphragm having a gas supply inlet and an outlet to said main burner upon one side of said diaphragm, and an outlet to said pilot burner and a vent to the atmosphere, upon the other side of said diaphragm; thermostatic means arranged to automatically open and close said pilot burner; and means movable to open and close said vent.

In testimony whereof, I have hereunto signed my name at Conshohocken, Pennsylvania, this eleventh day of February, 1927.

VICTOR MAUCK.
